STRAND TENSION INDICATING DEVICE

Filed July 10, 1943

FIG. 1

UNITED STATES PATENT OFFICE

2,353,092

STRAND TENSION INDICATING DEVICE

Horace R. Thornton, Baltimore, Md., assignor to
Western Electric Company, Incorporated, New
York, N. Y., a corporation of New York

Application July 10, 1943, Serial No. 494,217

7 Claims. (Cl. 57—59)

This invention relates to strand tension indicating devices and particularly to such devices for use in strand handling machines of the general type disclosed in co-pending application Serial No. 452,027, filed July 23, 1942, the device being associated with means for stopping the operation of the machine when a given degree of inequality of tension exists in the strands.

In the manufacture of electrical communication cable, for example, the type produced in the above-referred-to type of machine, wherein individual conductors are twisted into pairs and the pairs are then twisted into a cable, it is very necessary, in establishing uniformity in the individual pairs of conductors, that the two twisted pairs of conductors should, at all times, travel under similar and constant tensions before being twisted together. Consequently, it is necessary, when inequality of tension develops between the twisted pairs of conductors, that it be immediately indicated and, upon a given degree of inequality in such tensions developing, that the machine be automatically stopped.

An object of this invention is to provide a simple and practicable device for indicating inequality of tensions between advancing strands associated therewith and cooperating with means for stopping the advance of the strands when a given degree of inequality of tensions exists in the strands.

In accordance with the above objects, the present invention, in the embodiment thereof, as applied to the above-referred-to type of strand twisting machine for forming electrical communication cables, comprises a horizontally reciprocatory bar normally held in a predetermined position relative to and extending transversely to the advancing twisted pairs of conductors by spring means, the bar carrying a sheave at each end over which the twisted pairs of conductors travel and an indicator movable with the bar and cooperating with indicia for indicating any movement of the bar against the action of the spring means and thus that a condition of unequal tension has developed in the pairs of twisted conductors advancing over the sheaves, and also which pair has the greater tension. Associated with the indicator are electrical limit switches effective, upon a given degree of inequality of tensions, to automatically stop the machine.

Other objects and advantages of the invention will more fully appear from the following de-

tailed description taken in conjunction with the accompanying drawing, in which

Fig. 1 is a diagrammatic plan view of a strand twisting machine showing a strand tension indicating device and associated means for stopping the machine embodying the features of the invention; and

Fig. 2 is an enlarged longitudinal central section of the tension indicating device and associated means shown rotated 90° from the position thereof in Fig. 1.

In the drawing, an embodiment of the invention is illustrated as applied to a strand twisting machine of the general type disclosed in the referred-to co-pending application, Serial No. 452,027, filed July 23, 1942, to which reference may be had for a more detailed disclosure of such machine and its operation. In Fig. 1, only such parts of the twisting machine are shown in broken lines as are necessary to a full understanding of one use of the device of this invention, indicated in general at 5.

The parts of the twisting machine which are shown in Fig. 1, are mounted on a base 6 having vertical housings 7. Journalled on and between the two left-hand housings 7 are two flier units, indicated in general at 10 and 11, each having two supply reels 12, only one of which is shown, arranged side by side on a common axis. In the operation of the machine, the flier units 10 and 11 are actuated to twist conductors 13 withdrawn from the reels 12 included in each flier unit into pairs, the conductors receiving one twist per revolution of their respective fliers upon approaching their sheaves 14 and another twist after passing over sheaves 15 and 16 of their flier units. The flier units 10 and 11 are driven in like directions at speeds sufficient to place overtwists in the pairs of conductors 13 to offset the tendency of a flier unit at the right hand end of the machine from untwisting the pairs when these pairs are twisted together in an opposite direction from that of their original twist.

Upon leaving the flier units 10 and 11, the conductors 13 are in twisted pairs, indicated at 18, which converge and pass through a hollow shaft 19 to a flier unit, indicated in general at 20, in which a capstan 21 is disposed, the flier unit 20 being journalled on and between the right hand vertical housings 7. The capstan 21 is rotated counterclockwise, as seen in Fig. 1, to cause advancement of the conductors 13 from their respective supply reels 12, through the flier units 10 and 11, and the pairs 18 through the

hollow shaft 19. The pairs 18 are twisted together in a direction opposite their original twists to form a cable, indicated at 23, due to the flier unit 20 being driven in a direction opposite that of the flier units 10 and 11. Thereafter, the cable 23 passes around the capstan 21 to effect a pulling connection between the capstan and the cable, after which the cable is fed over sheaves 24 and 25 to a takeup reel 26. A common power means, such as a motor 28, is provided for driving, through suitable interconnecting means, the various parts of the machine, although separate speed reducing units 29 and 30 may be employed for the left and right hand ends, respectively, of the machine.

With this general understanding of the machine and what it accomplishes and realizing the necessity of uniformity in the individual twisted pairs 18 of conductors 13 and that they should travel at all times under similar and constant tensions, attention is now directed to the strand tension indicating device 5 of this invention and its associated means for stopping the machine when a given degree of inequality of tension exists in the twisted pairs of conductors.

Secured to and extending horizontally from the inner vertical housing 1 at the left hand end of the machine is a support 32 having integral vertical standards 33 interconnected at their upper ends by a sleeve-like portion 34 with heads 35 at opposite ends. Extending freely through the bore of the sleeve-like portion 34 is a reciprocatory bar or rod 36. Fixed to the rod 36 intermediate its ends is an indicator or pointer 40, which, at one end is associated with indicia 41 marked on a plate 42 carried on the support 32, the opposite end of the indicator being arranged to actuate one of two plungers 43 of normally closed limit switches 44 carried on the support 32 upon the rod 36 being moved longitudinally a predetermined distance in either direction. As shown in Fig. 1, the limit switches 44 are connected in parallel in the circuit to the motor 28. Opposite slots 47 in the sleeve-like portion 34 permit longitudinal movement of the rod 36 with the attached indicator 40 and the arrangement is such that the rod is prevented from rotating. The rod 36 is normally yieldably maintained in a central position in the sleeve-like portion 34 with the indicator 40 registered with a center mark 48 of the indicia 41 by means of similar coiled compression springs 49 surrounding the rod at opposite sides of the indicator, the opposite ends of the springs abutting adjacent sides of the pointer and adjustable nuts 50 threaded into the heads 35, the rod 36 having a sliding fit in bores 51 of the nuts 50. The nuts 50 provide means for adjusting the compression of the springs 49 and also to balance the indicator 40. A sheave 52 is journaled upon each end of the rod 36 and the twisted pairs 18 of conductors 13 are guided in their advance from the flier units 10 and 11 over the sheaves.

Adjustable means are included in the reel supporting mechanisms of the flier units 10 and 11 of the strand twisting machine, which is fully described and disclosed in the above-referred-to co-pending application, for causing the conductors 13 to travel from the reels 12 of the flier units 10 and 11 and thereafter in the form of twisted pairs 18 under like and constant tensions. At times, due to various causes, the two pairs 18 of conductors 13 may not be under the same tension and, in such case, suitable adjustment is

made in the adjustable means provided in the referred-to reel supporting mechanisms.

In the use of the device 5 of this invention as applied to the above-noted strand twisting machine and assuming that the twisted conductor pairs 18 are advancing convergently from the flier units 10 and 11 to a common point under equal tensions over the sheaves 52 of the tension indicating device, the rod 36 will remain in its central position and the indicator 40 will, consequently, register with the center mark 48 of the indicia 41, thus indicating that a condition of equal tension exists between the pairs 18. Whenever a greater tension develops in one of the pairs 18, due to any cause, the rod 36 will be shifted in the direction of the pair having the greater tension until both pairs have reached equal tension. The resultant movement of the indicator 40, moving with the rod 36, away from the mark 48, immediately indicates that a condition of unequal tension from that desired has developed, and also which pair has developed the greater tension. Suitable adjustment is then made through one or the other of the previously referred-to means associated with the reel supporting mechanisms to again cause the desired degree of equality of tension between the twisted conductor pairs 18. When a given degree of inequality of tension develops between the pairs 18, the opposite end of the indicator 40 will engage and actuate one or the other of the plungers 43 of the normally closed limit switches 44 and thereby open the power circuit to the motor 28 to cause an immediate stoppage of the twisting machine.

From the foregoing description, it will be apparent that a simple and practicable strand tension indicating device is provided for use in strand twisting machines, which is effective to provide a visual indication of any inequality of tension between advancing strands or variations from desired different tensions between such strands, if such is the case. Also, in the case of such equalities or variations exceeding a predetermined degree, means cooperating with the tension indicating device is effective to cause an immediate stoppage of the machine.

It will be understood that the embodiment herein described is merely illustrative of the invention and one application thereof and that modifications can be made and it is capable of other applications.

What is claimed is:

1. A tension indicating device for a plurality of spaced strands during handling in a strand handling machine comprising a reciprocably mounted member, yieldable means for maintaining said member in a predetermined position, opposite portions of said member adapted to be engaged by said strands, and means including an indicator movable with said member for indicating movement thereof against the action of said yieldable means when undesired tensions exist in the strands.

2. A tension indicating device for strands being advanced in a strand handling machine comprising a reciprocably mounted member, yieldable means for maintaining said member in a predetermined position, rollers carried upon opposite ends of said member over which the strands advance, and means including an indicator movable with said member for indicating movement thereof against the action of said yieldable means when undesired tensions exist in the strands.

3. A device for indicating tension in advancing

strands in a strand handling machine comprising an apertured support, a reciprocable member movable longitudinally therein, said member having an enlargement intermediate its ends, apertured means at opposite ends of said support for guiding said reciprocable member, coiled compression springs surrounding said member at each side of and abutting at their adjacent ends opposite faces of said enlargement, the opposite ends of said springs abutting said apertured means, opposite ends of said member adapted to be engaged by said strands, and means including an indicator carried by and intermediate said faces of said enlargement for indicating movement thereof against the action of said springs when 15 undesired tensions exist in the strands.

4. A device for indicating tension in advancing strands in a strand handling machine which includes power actuating means therefor comprising a reciprocably mounted member, yieldable means for maintaining said member in a predetermined position, opposite portions of said member adapted to be engaged by said strands, means including an indicator movable with said member for indicating movement thereof against the action of said yieldable means when undesired tensions exist in the strands, and means responsive to a predetermined movement of said indicator when a given degree of undesired tensions exists in the strands to interrupt the operation of the power actuating means of the machine.

5. A tension indicating device for a machine in which spaced strands are advanced convergently to a common point comprising a re-

ciprocably mounted member movable transversely of the direction of advance of the strands, means including yieldable elements effective for maintaining said member in a predetermined position, opposite portions of said member adapted to be engaged by said advancing strands, and means including an indicator movable with said member for indicating movement thereof against the action of said yieldable elements when unequal tensions exist in the strands.

6. A tension indicating device for a machine in which spaced strands are fed convergently to a common point comprising yieldably mounted means engaging the spaced strands and movable in opposite directions transversely of the direction of advance and in accordance with the differential of the tensions in the strands, and means cooperating with said strand engaging means to indicate said differential.

7. A tension responsive device for a strand handling machine which includes power actuating means therefor in which spaced strands are fed convergently to a common point comprising yieldably mounted means engaging the spaced strands, means cooperating therewith responsive to the differential of the tensions in said strands to indicate said differential, and means operable by said yieldably mounted means in response to a predetermined variation in the differential of the tensions in said strands to interrupt the operation of the power actuated means of the machine.
